F. W. DEITZ

ADJUSTABLE SPACING TOOL

Filed May 2, 1921

UNITED STATES PATENT OFFICE.

FRANK W. DEITZ, OF CLEVELAND, OHIO.

ADJUSTABLE SPACING TOOL.

Application filed May 2, 1921. Serial No. 463,120.

To all whom it may concern:

Be it known that I, FRANK W. DEITZ, a citizen of the United States, and resident of Cleveland, in the county of Cuyahoga and 5 State of Ohio, have invented certain new and useful Improvements in Adjustable Spacing Tools, of which I hereby declare the following to be a full, clear, and exact description, such as will enable others skilled 10 in the art to which it appertains to make and use the same.

The objects of the invention are to provide an improved device or instrument for ruling a multiple number of parallel lines 15 or for marking a number of spaced positions upon a plane or curved surface, either circumferentially or longitudinally thereof, the positions being equally spaced apart.

It also provides means for adjustably 20 supporting a multiple number of marking instruments such as graving points, pens, or pencils, in such a manner that the position of any one point can be changed relatively to the positions of the other points 25 and variations in the spacing of the points can therefore be readily obtained.

The instrument is adapted for the use of carpenters, joiners, cabinet makers and draftsmen of all trades, where the spacing 30 of lines on materials for joining or overlapping, or the spacing of openings can be accurately determined without taking repeated measurements.

The invention is hereinafter more fully 35 described, shown in the accompanying drawings, and specifically pointed out in the claims.

In the accompanying drawings Fig. 1 is 40 a plan of the device, adapted to operate upon a flat surface, Figure 2 is a similar view showing the device adapted to operate upon a curved surface, Figure 3 is an end elevation thereof, Figure 4 is a transverse section of one of the pivotal joints, Figure 5 is an enlarged plan thereof and Fig. 6 is a perspective showing the mode of attaching the scale member.

In these views A represents a graduated 50 strip or scale formed of flexible material so that it will bend readily.

B, B, are bars slidingly and longitudinally movable upon said scale, and extend upon one side thereof at right angles thereto.

C, C, are pencil or pen holders which are 55 pivotally mounted upon the aforesaid bars

D, D, and are provided with clamps E adjustable at F, F, in which the drawing or marking tools are held.

The holders C are also longitudinally movable of the bars, this adjustment being permitted by means of slots G, G, therein, and clamping screws D, D, which permit also of turning the tool holders from one side to the other, and permit horizontal movement in all directions, whereas the pivot at F, permits of vertical adjustment only.

The bars B, B, are made in two telescoping portions, the portion B' sliding in the portion B.

These bars are connected together by 70 means of pairs of crossed links H, H, pivoted at their ends to the respective portions B and B' of the bars, and the bars in each pair are pivoted together by clamping screws I, I, secured in spaced openings J, J, 75 in the bars.

By means of this construction all the bars can be moved together and a uniform distance will be preserved between the bars, thus permitting the device to be employed 80 for drawing lines uniformly spaced apart.

To permit the bars to move longitudinally of the scale, and to be connected by the crossed links, the outer ends B' of the bars must move longitudinally in the other portions, thus preserving the rigidity of the 85 device.

The links are preferably countersunk or provided with marginal recesses K, K, 90 around the openings J, J, and corresponding projections I, I, upon the adjacent link, which fit together.

A thin washer M prevents interference when the links are moved over each other. This adjustability of the bars and their connecting links, and the flexibility of the scale member permits the same to be bent into any desired arc or curve, regular or otherwise, and when properly adjusted to required 95 shape the clamping screws I secure the parts 100 in place.

When the tool holders C are in alignment with the bars B, the spaces between the points of the tools will be uniform, but when the holders are swung to one side of the bars 105 or the other, the spaces will be varied in width as desired.

As shown in Fig. 6, the flexible scale A, is shown secured in its bracket by cutting out a tongue A', from the vertical face A², 110

and folding it behind the scale, thus having an opening A³, through which the scale can be read.

A set screw A⁴, can be employed to prevent the scale member from sliding in its bracket in one of the bars. This will not prevent the other bars from moving in their respective brackets.

Having described the invention what I claim as new and desire to secure by Letters Patent is:

1. In a device for spacing and ruling parallel lines, the combination with an elongated scale member, of spaced bars slidably movable thereon, crossed links pivoted together in pairs, and adjustably connecting said bars and adapted to retain the same in parallel relation to each other, and drafting means adjustably secured to said bars adjacent to said scale member.

2. In a device for spacing and ruling parallel lines, the combination with a flexible scale member, of a multiple number of bars longitudinally slidable thereon, vertically and horizontally adjustable drafting means mounted upon each bar, pairs of crossed links, the links in each pair pivoted together

intermediate of their ends, said links adjustably connecting said bars, and adapted to retain them in parallel relation to each other, the connecting means for the outer extremities of said links being longitudinally movable in said bars.

3. In a device for spacing and ruling parallel lines, the combination with a flexible elongated scale member, of transversely placed bars, said bars slidably mounted upon said scale member, drafting means adjustably secured to said bars adjacent to said scale member, and crossed pairs of links connecting said bars, each pair connecting adjacent bars, the outer extremities of said links longitudinally movable of said bars, said links provided with spaced pivotal openings, and pivot pins adapted to be placed in turn in said pivotal openings to permit of flexing said scale to conform to any desired curvature.

In testimony whereof, I hereunto set my hand this 23rd day of March, 1921.

FRANK W. DEITZ.

In presence of—

SOL W. WYMAN,
WM. M. MONROE.
